Primary Examiner — Michael A. Pratt(74) *Attorney, Agent, or Firm* — Ladas & Parry LLP(57) **CLAIM**

The ornamental design for a key collector, as shown and described.

DESCRIPTION

FIG. 1 is a front elevational view of a key collector showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof.

The broken lines are included for the purpose of illustrating portions of the key collector that form no part of the claimed design.
